DESIGN FOR A SCARF HOLDER OR SIMILAR ARTICLE

Michael Chernow, New York, N. Y.

Application January 6, 1948, Serial No. 143,554

Term of patent 7 years

(Cl. D17—10)

To all whom it may concern:

Be it known that I, Michael Chernow, a citizen of the United States, and residing at New York, in the county of New York and State of New York, have invented a new, original, and ornamental Design for a Scarf Holder or Similar Article, of which the following is a specification, reference being had to the accompanying drawing, forming part thereof, and in which

Fig. 1 is a front elevational view of a scarf holder or similar article, showing my new design.

Fig. 2 is a side elevational view thereof,

Fig. 3 is a top plan view thereof, and

Fig. 4 is a bottom plan view thereof.

I claim:

The ornamental design for a scarf holder or similar article, substantially as shown.

MICHAEL CHERNOW.
